ENGBERT HARMEN REERINK AND AART VAN WIJK, OF EINDHOVEN, NETHERLANDS,
ASSIGNORS TO N. V. PHILIPS' GLOEILAMPENFABRIEKEN, OF EINDHOVEN, NETHERLANDS

PROCESS OF PREPARING VITAMIN D

Application filed June 9, 1930, Serial No. 460,066, and in the Netherlands July 20, 1929.

This invention relates to an improved process of preparing vitamin D.

It is well known that ergosterol on being subjected to radiation by ultra-violet light 5 is converted into vitamin D, a product which has proved to be of great value as a remedy against rachitis.

The invention has reference to a process of preparing vitamin D in this manner and 10 has for its object to increase the efficiency of the radiation.

The unsatisfactory results obtained heretofore have been imputed inter alia to the 15 action exercised by the light used for radiation on the vitamin D produced, since the latter is partially decomposed by ultra-violet light into products which hereinafter will be referred to as "demolition products". It has been proposed to avoid this decomposition 20 into alia by weakening a definite region of the ultraviolet spectrum which was believed to bring about the said decomposition and to be the absorption zone of vitamin D, and weakening it to such an extent that according 25 to the prevailing opinion it caused no longer any serious decomposition of vitamin D into "demolition products".

In contradistinction to existing theories it 30 has now been found that the part of the spectrum to which the decomposition of vitamin D was imputed is not to any extent more active in this respect than the remaining part of the ultra-violet spectrum. It is therefore comprehensible that a satisfactory 35 improvement was not obtained by means of the weakening operation resorted to.

There is however a further reason why the 40 methods of operation hitherto known were not so effective as the process hereinafter described, since it has now been found that on ergosterol being subjected to radiation not only vitamin D but also a number of products are formed which were unknown heretofore. There substances, which in distinction from 45 the decomposition products of the vitamin D

produced will be referred to hereinafter as "by-products", are comparatively valueless as they practically do not exercise any anti-rachitic action and are to be regarded therefore as impurities of the vitamin D produced. 50

In addition it has been found that the ultraviolet spectrum is possessed of zones in which the light rays are essentially active in connection with the production of vitamin D and form few by-products or no by-products at all and also that it is possible to indicate an additional zone of shorter wavelengths which practically produces no vitamin D but to which the formation of by-products is essentially due. 55

According to the invention a hitherto unknown useful effect is obtained by using for the radiation to which ergosterol is to be subjected ultraviolet light while filtering out wavelengths of the order of 270 m μ or less and discontinuing such radiation before more than approximately 60% of the ergosterol has been transformed. Thus the formation of any demolition products in such amount as to affect the purity of the vitamin D to a serious extent is avoided. Further, it has been found that it is desirable that the light used should be substantially devoid of wavelengths greater than 300 m μ ; however, it is obvious that any part of the spectrum which has no effect upon the ergosterol need not be filtered out. 70

The process according to the invention may be carried out by means of a filter absorbing the undesired rays and letting through as far as possible the vitamin D producing rays or by using a light source that emits no rays exercising an undue action on ergosterol. Generally, a sufficient result may be obtained 80 by means of light emitted from a suitable light source, say a mercury arc lamp, said light being caused to pass through a filter formed by a quantity of preferably dilute benzene. As a condition actinic rays which are of no essential importance in connection 85 90

with the formation of vitamin D should be adsorbed by the filter to such a great extent that practically they do not act on ergosterol, and the remaining ultra-violet rays should be transmitted in a possibly undisturbed manner. Obviously, the thickness of the filter depends greatly on the concentration. When a 5% solution of benzene is used, other circumstances being suitable, satisfactory results may be obtained, if the thickness of the filter is say about 10 millimetres.

In certain cases, for example if an electric discharge in magnesium vapour is used as the source of light, it may be desirable that the exclusion should be carried further and rays shorter than 282 $m\mu$ should be excluded.

It is true that rays having a wave-length between 270 and 282 $m\mu$ are absorbed by ergosterol in a comparatively intense manner, but particularly if powerful intensities occur in this region a deleterious effect is also to be attributed to such rays. It is therefore preferable that light having a wave length below 282 $m\mu$ should not be used, although the reaction will consequently be carried out in a slightly less rapid manner.

For the purpose above described a filter containing paraxylol is quite adapted for use, particularly in conjunction with an electric discharge in bismuth, or mercury vapour or with a similar light source.

The duration of the radiation is dependent upon the intensity of the light source, upon the degree to which the rays are absorbed and upon the quantity of the preparation to be treated. The radiation must not be continued until all the ergosterol has been transformed, because by and by part of the vitamin D produced is decomposed into demolition products so that the efficiency is lowered. For that reason, the treatment is terminated before more than approximately 60% of the ergosterol has been transformed. In the case of using a mercury arc lamp and a filter which is not too strong, a radiation for 10 minutes may suffice for the treatment of a quantity of ergosterol of about 1 milligram.

When subjected to the radiation the ergosterol may be in a solid state, but alternatively it may be dissolved in ether, hexane or other means for this purpose.

The invention will be more clearly understood by reference to the accompanying drawing in which

Figure 1 shows diagrammatically the arrangement of the devices used, and

Figure 2 is a different projection of one of these devices.

The ultraviolet light is radiated by a mercury vapour lamp 1 comprising a mercury electrode 2 and a solid electrode 3. The current is supplied to the tube from a transformer 4 with the interposition of a series resistance 5. The wall of the tube is of quartz which is transparent in a substantially uni-

form manner to the light radiated by the mercury arc. This light strikes a bulb 6 in which the substance to be subjected to radiation is enclosed. The light rays pass, however, through an interposed bulb 7 the wall of which is of quartz similarly to that of 6. The vessel 7 is filled with a liquid, for example a benzene solution, which arrests light having a wave-length shorter than 270 $m\mu$, or with still greater advantage a substance that absorbs rays up to 282 $m\mu$, but which on the contrary lets through longer wavelengths in a substantially undisturbed manner. The bulb 6 contains a solution of ergosterol in ether, hexane or the like. This vessel has sealed to it tubes 8 and 9 through which the liquid can be delivered or discharged, a continuous production being thus ensured. The speed at which the liquid flows through the vessel 6 may be controlled so as to ensure a maximum antirachitic action of the preparation subjected to radiation.

Figure 2 is a sectional view of the bulb 7 which is formed by a small cylinder of quartz 10 sealed at both ends by small plates 11 which are also of quartz. The cylinder has sealed to it tubes 12 and 13 which permit of the vessel being exhausted and the liquid being introduced. After the vessel has been filled, these tubes are sealed off. The remaining parts of the tubes may serve for supports.

What we claim is:—

1. In a process of preparing a material containing vitamin D, the steps comprising subjecting ergosterol to radiation by artificially produced ultraviolet light while filtering out light of wave lengths of the order of 270 $m\mu$ or less, and discontinuing such radiation before more than approximately 60% of the ergosterol has been transformed.

2. In a process of preparing a material containing vitamin D, the steps comprising subjecting ergosterol to radiation by artificially produced ultraviolet light while filtering out light of wave lengths shorter than 282 $m\mu$, and discontinuing such radiation before more than approximately 60% of the ergosterol has been transformed.

3. In a process of preparing a material containing vitamin D, the steps comprising subjecting ergosterol to radiation by artificially produced ultraviolet light while filtering out light of wave lengths of the order of 270 $m\mu$ or less and substantially all of the light of wave lengths greater than 300 $m\mu$, and discontinuing such radiation before more than approximately 60% of the ergosterol has been transformed.

4. In a process of preparing a material containing vitamin D, the steps comprising subjecting ergosterol to radiation by artificially produced ultraviolet light while filtering out light of wave lengths shorter than 282 $m\mu$ and substantially all of the

light of wave lengths greater than 300 m μ , and discontinuing such radiation before more than approximately 60% of the ergosterol has been transformed.

5. In a process of preparing a material containing vitamin D, the steps comprising subjecting ergosterol to radiation by light of wave length substantially limited to the band between 282 m μ and 300 m μ , and discontinuing such radiation before more than approximately 60% of the ergosterol has been transformed.

In testimony whereof we have signed our names to this specification.
